N. W. Bonney

UNITED STATES PATENT OFFICE.

N. W. BONNEY, OF VICTORIA, TEXAS.

BOLT FOR DOORS.

Specification of Letters Patent No. 28,827, dated June 26, 1860.

To all whom it may concern:

Be it known that I, N. W. BONNEY, of Victoria, in the county of Victoria and State of Texas, have invented a new and useful 5 Improvement in Bolts for Doors, &c.; and I do hereby declare that the following is a full, clear, and exact description of the same, reference being had to the accompanying drawings, forming a part of this specification, in which—

Figure 1, represents a front view and partial section of the door when open. Fig. 2, a vertical section of the door when locked, and Fig. 3, a horizontal cross section.

15 Similar letters of reference, in each of the several figures indicate corresponding parts.

The nature of my invention consists 1st. In the combination of a lever, stop, cam and 20 spring with the two wings of a door in the manner and for the purpose hereafter to be described.

To enable others, skilled in the art, to make and use my invention, I will proceed 25 to describe its construction and operation.

The sill of the door is provided with a recess *s*, for the reception of a lever *a*, pivoted in its center at *n*. The bottom of this recess is closed with a plate *g*, made with two 30 holes for the pin or stop *j*, and the cam shaped projection *i*, to work through. The stop *j*, and cam *i*, are arranged at the opposite ends of lever *a*, and project from the lever downward. They are both of such 35 length that the one projects through and below the plate *g*, while the other one is pressed back above the plate *g*, and vice-versa. The cam *i*, is arranged above that door wing *m*, which contains the bolt of 40 the door lock *h*, and the stop *j*, is arranged above the other wing *n*, containing the recess into which the bolt locks. The top edge of 45 the wing *m*, carries a shield plate *o*, and the top edge of wing *n*, a similar plate *p*, the latter being provided with a hole corresponding with the situation of stop *j*, and with a recess *f*, in the top of wing *n*.

When it is desired to lock both wings of the door, the wing *n*, is closed first, which 50 can be done as the stop *j*, is held above the plate *g*, so as to be out of the way, by the action of a spring *b*, which is fastened inside of the recess *s*, at *c*, and serves to press down the other or cam end of the lever *a*. After 55 the wing *n*, has been closed, the wing *m*, is also closed. While the latter wing is being

closed down, so as to cause the bolt of the door lock *h*, to drop into the corresponding recess in wing *n*, the cam *i*, comes in contact with the plate *o*, at the top edge of door-wing *m*, and this end of the lever is pressed up until the cam *i*, is above the plate *g*. This of course causes the other end of the lever and stop *j*, to move down until the stop enters through the hole in top plate *p*, into recess *f*, in the top edge of wing *n*. It will be seen that by this means, both wings of the door are simultaneously locked and the door cannot be opened except by withdrawing the bolt of lock *h*, and first opening wing *m*, 70 thereby allowing the spring *b*, again to depress the cam end of lever *a* and raising the stop *j*, out of recess *f*, after which the other wing *n*, can also be opened. The advantage of this arrangement is that by closing the 75 wings *n*, and *m*, (in the manner above described) both wings of the door are automatically locked, an advantage which could not be obtained by using only one stop or cam in combination with a simple spring 80 without the double acting lever *a*. Another and an important advantage is that when one wing of the door is swung open, the other is automatically unbolted and can be instantly opened without applying the hand 85 to the bolt.

In all window and door fasteners with which I am familiar, the bolt has to be operated by the hand or thumb and therefore if the bolt is situated on top of the door, considerable difficulty of reaching it is experienced.

My bolt affords great safety, for if one wing is locked, the other will necessarily be bolted.

I do not claim a fastening which has to be operated by hand, as seen in Hochstrasser's patent of 1853, but

What I do claim as my invention, and desire to secure by Letters Patent, is— 100

The combination of a lever stop *j*, cam *i*, and spring *b*, with the two wings *m*, *n*, of a door, when the same is so applied that the closing of the two wings brings the bolt into effective action and the opening of the wing which has the lock applied to it allows the bolt to automatically cease its action, as herein set forth.

N. W. BONNEY.
